METALLIC ROPE AND CABLE

Alvin L. Noyer and Alexander McEachern, Portland, Oreg., assignors to Wickwire Spencer Steel Company, New York, N. Y., a corporation of Delaware

Application July 16, 1940, Serial No. 345,816

7 Claims. (Cl. 57—147)

This invention relates to all wire rope or cable (except locked wire rope or locked coil cable) having practically any type of strand construction and either a fiber core or an independent wire rope core and is not affected by the lay of the wire rope.

The quintessence of our invention is to provide soft wires made of lead, or an alloy metal possessing similar qualities as lead, in wire rope having a core and a plurality of strands made of wires substantially harder than the lead wires or similar alloy and positioning them in the helicoidal interstices, commonly known as valleys, formed between the outer strands of the wire rope so that they form the base of these valleys and prevent said strands from contacting and binding each other.

The causes of premature wear and destruction of wire rope are many. Among some of them are the improper alignment of sheaves; the use of sheaves and drums having the wrong tread size; improper gapping between the strands which usually results in the unequal division of the load on the strands and thereby causing high strands; and the binding of adjacent strands causing the nicking of the strand wires in the valleys of the rope. There are other causes of rope wear which are inherent in the present type of wire rope construction. These include the normal tolerance allowed in manufacture for permitting the strands to adjust themselves relative to each other and to the core; the inherent elasticity in the strands, the degree of which is determined by the length of lay of each strand, the stretching of the whole rope under load, and the sliding and creeping of the strands relative to each other in order to come into perfect balance during the bending of the rope over sheaves and drums. All of these factors of movement, pressures, and stresses and many others produce undesirable frictional engagement between the strands that cause a reduction of the service life of the wire ropes as they are now manufactured.

It is within the contemplation of our invention to overcome the inherent disadvantages of the present type of wire rope construction. This is accomplished by incorporating into wire rope of means which will, in some measure, alleviate, if not completely eliminate, a great many of the causes for wire rope wear.

The main object of our invention is to incorporate in wire rope of the types now manufactured of means for prolonging its life and increasing its durability without appreciably diminishing its elasticity, flexibility and tensile strength and

without affecting its compactness, or basically altering its construction.

Another object of our invention is to incorporate into wire rope of the types now manufactured wires made of a soft metal such as lead or alloy of similar qualities, which act as buffers and take up and cushion the radial compressive load caused by the stretching and readjustment of the strands under load so that any friction created by these various movements is normally not between the wires in the strands but between the strand wires and the soft wires.

Still another object of the invention is to provide means which materially assist in preventing the entrance of foreign subject matter into the core of the wire rope and which materially reduces the corrosion of the under portions of the strands of the wire rope.

One of the important objects of our invention is to fabricate into and make a part of the wire rope of means which will practically eliminate the common fault of adjacent strands nicking each other and which will materially minimize the internal friction between the strands.

For a full understanding of the invention and the advantages to be derived therefrom and also to acquire a knowledge of the details of construction and the means employed for effecting the results, reference must be made to the following detailed description and to the accompanying drawing, in which:

Figure 1 is a detail, transverse, sectional view of a fancifully constructed wire rope or cable embodying the principles of our invention;

Figure 2 is a detail, transverse, sectional view of a fancifully constructed wire rope or cable constructed in accordance with the principles of this invention, showing an independent wire rope as the core which itself embodies the principles of our invention; and

Figure 3 is a perspective view of the end of a fancifully constructed wire rope or cable constructed as shown in Figure 2 with some of the strands removed to more graphically depict the position of the soft wires relative to the strands and to each other.

Corresponding and like parts are referred to in the following description and indicated in all the views of the drawing by the same reference characters.

The views in the drawing disclose, for illustrative purposes only, wire ropes fabricated from strands incorporating various types of strand construction which are employed to form a complete wire rope or cable. It should be understood,

therefore, that the intent of such a disclosure is merely to illustrate graphically that our invention is adapted for use in wire ropes or cables fabricated not only from the representative strands shown in the views, but also from practically every other type of strand construction.

Referring now to Figure 1, there is shown a cross sectional view of a wire rope, designated generally by reference character A, which has a fiber core 1 made of hemp or any other suitable material. A plurality of hard wire strands of uniform cross section, generally designated by reference character B, are helically wound compactly around the core 1. It is obvious that any number of layers of strands may be employed, depending upon the size of wire rope or cable that it is desired to produce.

During fabrication of practically all types of wire rope, helicoidal interstices 2, customarily called valleys, are formed between the strands B. Wires 3, possessing the desired predetermined cross-sectional area and made of soft metal, such as lead or an alloy possessing similar qualities, are positioned within and form the bases of the interstices or valleys 2 and are adapted to maintain the outer strands B, which form a part of the completed rope A, out of intimate contact with each other. The shape of these soft wires 3 at the time of their incorporation into the wire rope A may be round, square or rectangular in cross section, or may have any other desirable shape; but regardless of the original shape of these wires 3, the radial pressure and the other movements of the strands of the wire rope A under load normally cause the wires or strands 4 and 4', as the case may be, which define the transverse limits of the interstices or valleys 2, to embed themselves in the soft wires 3 and to normally form shallow, helical grooves, as shown at 5 and 5', in the sides of the said soft wires 3. By positioning the soft wires 3 as stated, it at once appears obvious that there is an alternating arrangement between the outer strands B and the soft wires 3 and that, regardless of the deformation of the soft wires 3, this alternation arrangement exists at all times and prevents the wires or strands 4 and 4', as the case may be, which define the limits of the interstices or valleys 2, from contacting each other.

The positioning of soft wires 3, as shown in Figure 1, alternately between the sides of the strands B has the effect of practically sealing the core from the entrance of foreign matter through the interstices 2, especially when the sides of the strands embed themselves into the sides of the soft wires. Furthermore, the positioning of the soft wires 3 as illustrated and described has the effect of shifting to the soft wires 3 the greatest portion of the strand-destroying friction which the contacting strands heretofore were required to withstand. It should be noted that the insertion of the soft wires 3 into the wire rope A is not primarily for the purpose of increasing the tensile strength of the rope structure, although the soft wires may have sufficient tensile strength to take care of their own weight which necessarily is added to the weight of the wire rope A. Therefore, it is obvious that the destruction of one or more of the soft wires 3 does not materially affect the tensile strength of the rope in which they are positioned. It also must be pointed out that, should any portions of these soft wires 3 become destroyed through use, the remaining portions would continue to perform their function of prolonging the

life of the wire rope into which they are inserted.

The applicability of the invention to a wire rope or cable which has an independent wire rope center is graphically illustrated in Figures 2 and 3. In these figures reference characters B' designate generally the outer strands of the wire rope or cable designated generally by reference character A', and reference character C designates generally the outer strands of the independent wire rope center core designated generally by reference character D. Soft wires 8 are positioned in the interstices 7 formed during the fabrication of the independent wire rope D forming the center of the completed wire rope A'. Soft wires 6 possess the identical structural and other characteristics and perform the same functions as heretofore related in describing soft wires 3 disclosed in Figure 1. These soft wires 6 are compressed by those wires of the strands C which define the transverse limits of the interstices 7 and seal the interior of independent wire rope D. The interstices 8 formed between the outer strands B' of wire rope A' are also filled to the appropriate limits by soft wires 9 which possess the structural and other characteristics and perform the identical functions as are performed by the soft wires 3 disclosed in Figure 1 and soft wires 6 forming a part of the structure of the independent wire rope D forming the center of wire rope A'. By fabricating a wire rope in the manner illustrated in Figures 2 and 3 heretofore described, an appreciably greater degree of durability and extension of the life of a rope so constructed is attained, because of the advantages heretofore pointed out in describing the structural characteristics of a wire rope constructed as shown in Figure 1 and, also, because the sealing of the interstices 7 of the independent wire rope D, which forms the center of the wire rope A', insures against any material displacement of the outer strands B' from their position upon the crowns 10 of their respective strand C forming a part of the independent wire rope D. This is a common fault in the construction of the present type of wire ropes having an independent wire rope center, because of the fact that it is common practice to make the lay of the outer strands of an independent wire rope center shorter than the lay of the outer strands of the wire rope of which it is a part.

Having described the details of construction and pointed out the functions and advantages of the invention, we assert that it is not our wish to be limited to the exact shape and size of the soft wires or to their exact position shown in the drawing, for their shape, size and position may be varied in some degree without materially departing from the spirit and scope of our invention as defined in the appended claims.

What we claim is:

1. In a wire rope or cable of the class described composed of a central core and a plurality of strands surrounding said core, of means for preventing the adjacent sides of the strands from contacting each other, said means having a high degree of ductility and permitting the embedding therein of those strand wires which define the transverse limits of the valleys formed between said strands.
2. In a wire rope or cable composed of a core and a plurality of strands helically positioned around the core and forming a single unit therewith, of a soft wire disposed between each of said strands adapted to prevent each of said strands from contacting each other, the cross-sectional

area of each of said wires being smaller than the cross-sectional area of each of said strands.

3. In a wire rope or cable composed of a central core and a plurality of strands helically positioned around the core and forming a single unit therewith, a plurality of soft wires helically disposed between the sides of said strands and forming the base of but not completely filling the interstices provided between said strands, said wires adapted to act as buffers and to cushion 10 the radial pressure placed on the rope or cable under load.

4. In a wire rope including a central core and a plurality of outer strands covering said core, of a plurality of soft wires, equal in number to 15 the number of strands covering said core, positioned in but not filling the interstices formed between the strands and forming the bases thereof, said wires adapted to be helically grooved by the pressure of the strands and to thereby seal 20 the core against entrance therein of foreign matter.

5. A wire rope including a center core and a plurality of outer strands covering said core, of a plurality of lead wires or wires made of an alloy 25 possessing substantially the same qualities, equal in number to the number of strands covering said core, positioned in but not filling the interstices formed between the strands and forming the bases thereof, said lead wires adapted to be helically grooved by the pressure of the strands and to thereby seal the core against entrance therein of foreign matter.

6. A wire rope or cable comprising a body formed of a central core, a plurality of strands peripherally arranged in helical relation to each other around said core, said strands fabricated from hard wires, and a plurality of soft wires arranged in helical relation to said core and said strands, said strands and soft wires being disposed in alternating relation to each other with the soft wires forming the bases of but not filling the interstices found between the strands, and those wires of the strands which define the transverse limits of the interstices adapted for being embedded in the sides of the soft wires, when the wire rope or cable is placed under load.

7. As a new article of manufacture, a wire rope or cable possessing the well-known structural characteristics, and soft wires, possessing the desired cross-sectional area for forming the base for but not completely filling each of the interstices or valleys located between the strands of the wire rope or cable, disposed between the sides of the outer strands of said type of wire rope or cable, said soft wires adapted to prevent the outer strands from contacting each other and permitting those wires of said strands which define the transverse limits of the interstices or valleys to embed themselves therein, thereby to form shallow helical grooves on the sides of the soft wires.
